MACHINE FOR FORMING OIL-CAKES.

1,302,246.

Specification of Letters Patent. Patented Apr. 29, 1919.

Application filed July 30, 1917. Serial No. 183,430.

To all whom it may concern:

Be it known that I, RUSSELL A. TRACE, a citizen of the United States, residing at Dayton, in the county of Montgomery and State of Ohio, have invented certain new and useful Improvements in Machines for Forming Oil-Cakes, of which the following is a specification, reference being had thereto to the accompanying drawing.

10 This invention relates to machines for forming oil cakes, though many of its features are not limited to this particular use.

The improvements relate to the construction of the forming press. A principal object is to provide an improved hydraulic press particularly adapted for forming oil cakes and also usable in other relations, the improvement comprising a method of operation whereby a much smaller amount 20 of oil or other liquid under pressure is required to operate the press.

The invention is illustrated in the accompanying drawings, in which:

Figure 1 is an end elevation of the press 25 proper showing also a stand pipe or reservoir for liquid;

Fig. 2 is a side elevation of the press, but showing the hydraulic ram and its cylinder and operating valves in section; and

30 Fig. 3 is a side elevation of the press similar to Fig. 2, but showing the ram elevated and with some of the parts of Fig. 2 shown in side elevation.

The construction and operation of the 35 press may be next described, and it will be understood that the liquid under pressure which is used to operate the press is supplied from a pump of any desired type driven by some motive power such as a 40 steam engine or an electric motor. In order to equalize the work on the pump, the system includes an accumulator of some well known type into which the liquid is forced by the pump. The accumulator may be of 45 the type having a heavy weight which serves to maintain a substantially constant pressure of the liquid. Thus the pump works continually against this constant pressure and its work is thereby equalized. In the 50 use of such a system employing an accumulator there is a decided advantage in arranging the system to require as little liquid to be pumped as possible because it is pumped against a constant pressure.

55 To provide for the use of a small amount

of liquid is one of the objects of the present invention. This object is obtained by constructing the press so that during the greater part of the stroke of the ram only a small area is exposed to the liquid pressure. This part of the stroke is occupied in bringing the mold box nearly up to the press head and the only resistance to this part of the movement is the weight of the meal and the weight of the moving parts, 60 such as the ram and the cross head. When the mold box reaches the position at which pressure commences to be exerted on the meal, a much higher pressure is necessary and the construction herein is such that at 65 this stage of the operation a much larger area of the ram is exposed to the liquid pressure from the accumulator. This second part of the stroke is comparatively small in extent and therefore does not require any 70 great amount of liquid for its operation.

Referring now to Figs. 1, 2 and 3, it will be seen that in Fig. 2 the ram is just starting upward, the operating handle having been actuated by the workman, while in 75 Fig. 3 the handle has been released and the ram is just starting down.

The press as a whole is mounted on a base plate 70 which may in fact support the entire machine and which bears standards 71 80 and 72 supporting the press head 9 and forming block of the press. The cylinder 7 is provided with the ram 74 which serves to elevate the cross head 73 and the mold box 8.

90 The valve mechanism controlling the entrance of the liquid is shown in Figs. 2 and 3 and is operated by a lever not shown carried by a rod 100 and fast to this is an arm 101 which has a slot and pin connection with 95 the valve stem 102. The liquid enters the device at the port 75 and passes around a cut away portion 75^a of the valve stem. When the operating handle is depressed to operate the ram the valve stem 102 is elevated and the liquid may then pass from entrance port 75 through the cut away portion 75^a, then through port 87 and through a passage 80 giving entrance to a standard 100 81 carried by the cylinder 7 and around 105 which the ram 74 is guided. This standard 81 has a vertical passage 82 for the liquid, leading from passage 80 and through which the liquid passes upward and into the chamber 83 in the ram. It will be seen that this 110

chamber has a comparatively small cross section and thus no great amount of liquid is required to lift the ram from the position of Fig. 2 to substantially the position 5 of Fig. 3. When the ram reaches the position at which pressure must be exerted on the meal, a greater amount of liquid pressure is required and this is obtained by providing a chamber 84 in the cylinder to which 10 liquid may be admitted whereby liquid pressure under the entire ram may be obtained. To attain this end, the standard 81 is pierced part way up its length by a port 85 from the vertical passage 82. The under side of 15 the ram is cut away, as indicated at 86, and it will be understood that as soon as the edge of this cut away portion opens the passage 85, liquid under pressure may pass through this passage and exert pressure under the whole of the under surface of the 20 ram.

It will be seen, however, that to fill the entire chamber 84 with liquid through passage 85 would require as much liquid under 25 pressure as if the liquid was admitted directly to chamber 84. To avoid this, means are provided for admitting enough liquid to chamber 84 to fill it as the ram moves upward, but this liquid need not be and is not 30 supplied by the accumulator, but is provided from a supply device shown as a standpipe 79. This standpipe is shown in Fig. 1 and it is connected by a large pipe 77 in which 35 is a check valve (not shown), which prevents oil passing from chamber 84 back to the standpipe through pipe 77. It will be understood that this pipe 77 opens directly into chamber 84 and as the standpipe 79 is continually full of liquid, the elevation of ram 40 74 by the liquid passing into the interior chamber 83 permits liquid to pass from the standpipe through pipe 77 and fill the chamber 84. In fact, the elevation of ram 74 by liquid entering chamber 83 will serve to suck 45 the liquid through pipe 77 if the standpipe has no part at a higher elevation than the cylinder 7 itself.

When the ram has been elevated sufficiently to compress the meal to the desired 50 extent, the operator releases the handle which thereupon permits the valve mechanism to return to the position of Fig. 3. In this position the cut away portion 75^a of the valve stem 102 connects the port 87 with the exit 55 pipe 78 running to the supply tank for the pump. The weight of the ram 74 and the parts carried thereby is sufficient to force it downwardly thereby carrying the liquid in chamber 83 out through passages 82 and 60 80 through port 87 to the exit pipe 78.

Also the liquid then in chamber 84 must be withdrawn and the weight of the ram and parts carried thereby is sufficient to effect this. It is not desired to withdraw the 65 liquid from chamber 84 through pipe 77, and

in fact, the check valve prevents this. To permit the withdrawal of the liquid in chamber 84, a pipe 89 is connected to a passage 88 running from chamber 84 and normally held closed by a valve 89^a. This valve normally prevents liquid passing from standpipe 79 through pipe 89 into the chamber 84. A passage 90 runs from port 87 into passage 88 above the valve 89^a. 70

When the valve mechanism is in the position of Fig. 2 and liquid enters the device through entrance port 75, it also passes through the passage 90 above the valve 89^a and forces the valve from the position of Fig. 2 to that of Fig. 3, thus entirely shutting off pipe 89. Thus no liquid can pass into chamber 84 from standpipe 79 through pipe 89, but must pass through the large pipe 77. 75

When the valve mechanism is moved to the position of Fig. 3, by release of the operating lever, the parts are restored to normal position. The cut away portion 75^a of valve stem 102 cuts off entrance port 75, and thus the valve 89^a is no longer held down (as in 90 Fig. 3) by the pressure of the liquid above it. The weight of the ram 74 and the parts carried thereby can then force the valve 89^a upwardly to the position of Fig. 2, thereby uncovering the return pipe 89 to the stand- 95 pipe 79. Then the liquid in chamber 84 is forced out through passage 88 and pipe 89 into the standpipe 79. If more is ejected than the standpipe will hold, the surplus moves through a pipe 91 connected to the top 100 of the standpipe back to the supply tank for the pump. Thus, the chamber 84 is filled with liquid from the standpipe 79 at each 105 operation of the press and this liquid together with whatever liquid passes through the port 85 into the cylinder 84 will be returned to the standpipe through exit pipe 89.

It will be understood that only a relatively small amount of liquid passes into the chamber 84 through the passage 85. To 110 this end the passage 85 is positioned at a point such that the cut away portion 86 of the ram will open this passage at substantially the point where the meal begins to be compressed and where therefore a much 115 higher pressure is necessary.

The specification has referred to the use of liquid and it will be understood that any desired liquid, such as oil, water or glycerin may be employed. 120

By the provision of the two chambers 83 and 84 it will be seen that the pressure of the liquid is effective on the entire diameter of the ram. That is, the pressure on the under side of the ram from the liquid in the 125 chamber 84 after passage 85 is open is added to the liquid pressure in the chamber 83. The sum of these two pressures is the same as would be the case if the ram was solid and not provided with the standard 81. 130

The pipe 79 has been referred to as a standpipe and with the parts as shown in Fig. 1 the liquid in this pipe will be under more or less pressure due to its gravity head. 5 The pipe 77 is always open into the chamber 84 of the ram, but the weight of the parts is so much that the liquid cannot pass from pipe 79 into the ram cylinder until the ram is elevated by the liquid under pressure 10 coming through entrance port 75. It is not desired to limit the invention to the use of a standpipe furnishing a gravity head as the device is entirely operative with a construction wherein the supply for the chamber 84 15 is entirely at a lower elevation than the chamber itself. In other words the liquid may well be sucked into the chamber 84 by atmospheric pressure on the pipe 79, whereby no effect due to gravity would be obtained. 20 For simplicity many of the claims recite "means for admitting liquid by suction" and this is done to emphasize the fact that no gravity head in the standpipe 79 is required. In fact, even when there is a gravity 25 head the action will be partly by suction because of atmospheric pressure on the standpipe.

The liquid passing from standpipe 79 to chamber 84 through pipe 77 is all returned 30 to the standpipe through the passage 89. Also whatever liquid passes 85 is carried to the standpipe. Thus, a slightly greater amount of liquid is returned to the standpipe at each operation than is taken from it 35 and this small surplus will return through pipe 91 to the supply tank for the pump.

In the claims the terms "pumped liquid" and "suction liquid" are employed and by these it is intended to distinguish the two 40 sources of liquid supply, one coming from some type of accumulator and being under high pressure, the other coming from a standpipe or liquid supply device and being supplied wholly by suction due to atmospheric pressure, or partly by such suction 45 and partly by gravity.

The pressing operation is readily accomplished by actuating the operating lever. The depression of this lever raises the valve 50 mechanism for the press to the position of Fig. 2, thus permitting liquid under pressure from the accumulator to pass through passage 80 and up the inside passage 82 into chamber 83 of the ram. The ram moves upward carrying its mold box and charge of meal and liquid from the standpipe 79 passes through pipe 77 past the check valve into the chamber 84, maintaining it completely filled with liquid. The valve 89^a at 55 this time prevents the passage of liquid through the pipe 89 from the standpipe, being held seated by the liquid pressure through passage 90. As the ram approaches the end of its upward stroke the passage 85 60 is opened and liquid under pressure may

then pass therethrough and complete the operation of raising the ram and pressing the meal. At this time the entire ram is under pressure both in the chamber 83 and in the chamber 84. When the meal has been 70 sufficiently compressed the workman releases the operating lever and the valve mechanism then returns to the position of Fig. 3. In this position the liquid supplied under pressure through passage 75 is cut off and 75 the return pipe 78 is opened. Thus, the liquid in the chamber 83 may pass out to the supply tank for the pump through passage 80 and the liquid in chamber 84 moves through passage 88 and pipe 89 into the 80 standpipe 79. This latter movement of liquid is permitted as the pressure through passage 90 is removed and the liquid in chamber 84 may readily elevate the valve 89^a. Any excess of liquid returned through pipe 89 to 85 the standpipe 79 moves through pipe 91 to the supply tank for the pump.

The economy in the use of liquid under high pressure in the press proper is very marked as only a relatively small amount 90 thereof is required compared to what would be necessary if the entire supply was furnished under the accumulator pressure.

Having thus fully described my invention, what I claim as new and desire to secure by 95 Letters Patent, is:—

1. In a hydraulic press, the combination, with the ram and a plurality of constantly separate force chambers, of a three-way valve for admitting fluid under pressure to 100 a force chamber, and means controlled by the movement of the ram for establishing communication between said chambers, whereby the fluid pressure is introduced successively into said chambers for operating the ram at varying powers, and a 105 gravity valve coöperating with the three-way valve to permit discharge of the fluid from said chambers.

2. In a hydraulic press, the combination 110 with the ram, of primary and secondary force chambers which are separate during the whole movement of the ram, a three-way valve for admitting fluid under pressure to the primary chamber, means for maintaining the secondary chamber filled with fluid as the ram is moved by the fluid pressure in the primary chamber, and a port for establishing communication between said chambers adapted to be opened by movement of 115 the ram for a part of its stroke, whereby fluid pressure is introduced into the secondary chamber for continuing the stroke of the ram at greater pressure, and a gravity valve coöperating with the three-way valve 120 to permit discharge of the fluid from said chambers.

3. In a hydraulic press, the combination 125 of concentric cylinders, a hollow ram telescoping with said cylinders, a three-way 130

valve for supplying fluid under pressure to one cylinder and for filling the other cylinder with fluid as the ram is moved at low pressure, and a port for establishing communication between said cylinders which is opened by movement of the ram for a certain part of its stroke, the ram continuing throughout its reciprocations in telescopic relation with the concentric cylinders, and a gravity valve coöperating with the three-way valve to permit discharge of the fluid from said cylinders.

4. In combination, a cylinder having a plurality of constantly separate force chambers, a tubular ram telescoping with the walls of said chambers, and means controlled by movement of the ram for establishing communication between said force chambers, with a three-way valve for admitting fluid under pressure to one force chamber and supplying fluid to fill the other force chamber, whereby the ram is moved rapidly until the fluid pressure is introduced into both force chambers for continuing the stroke at increased pressure, and a gravity valve coöperating with the three-way valve to permit discharge of the fluid from said chambers.

5. In combination, a cylinder having a plurality of constantly separate force chambers and a port, controlled by the ram, for establishing communication between said chambers, with a ram, and a three-way valve for admitting fluid under pressure to one force chamber to move the ram rapidly until it causes the opening of said port, whereupon the stroke is continued by the operation of fluid pressure in both chambers, and a gravity valve coöperating with the three-way valve to permit discharge of the fluid from said chambers.

6. The combination of a cylinder, a tube

within the cylinder provided with a lateral port, a hollow or bored ram working in said cylinder and on said tube, the ram when retracted covering said port, and a three-way valve for admitting fluid to the tube and cylinder and supplying the fluid under pressure to one of them, whereby the ram is moved quickly with low pressure until it uncovers said port and its stroke is then continued with greater pressure, the ram working on said tube at all times, and a gravity valve coöperating with the three-way valve to permit discharge of the fluid from said chambers.

7. In combination, a cylinder having a plurality of force chambers, a ram, pipe-connections for supplying fluid to both chambers and a three-way valve for supplying the fluid under pressure to one of them, means controlled by the ram for establishing communication between said chambers, and means whereby the fluid pressure can be introduced into both chambers before such communication is established, and a gravity valve coöperating with the three-way valve to permit discharge of the fluid from said chambers.

8. In a hydraulic press, the combination of concentric cylinders, a hollow ram telescoping with said cylinders, a three-way valve for supplying fluid under pressure to one cylinder, there being a port for establishing communication between said cylinders which is opened by movement of the ram for a certain part of its stroke, the ram continuing throughout its reciprocations in telescopic engagement with the concentric cylinders, and a gravity valve coöperating with the three-way valve to permit discharge of the fluid from said cylinders.

In testimony whereof, I affix my signature.
RUSSELL A. TRACE.
